GARMENT TRIMMING MACHINE

Henry Lehde, Brooklyn, N. Y., assignor to Samuel Shefsky and Louis Levy, Brooklyn, and Philip L. Rudick, New York, N. Y.

Original application March 2, 1940, Serial No. 321,894. Divided and this application December 2, 1941, Serial No. 421,297.

7 Claims. (Cl. 164—71)

This invention relates to improvements in dress or garment trimming machines and provides a fully automatic device for quickly and accurately trimming the bottom of a dress or the like to a straight line at any desired length, while it is on a dress form, this operation being commonly known as "sloping."

This application is a division of my application Ser. No. 321,894, filed March 2, 1940, for Garment trimming machine, and is, in part, a continuation of my application filed October 7, 1939, Ser. No. 298,434, now Pat. No. 2,192,446, granted March 5, 1940.

One object of the invention is to make it unnecessary to measure the length of the dress being cut, it being possible to cut any desired length of dress by a simple adjusting means.

Another object is to eliminate any necessity for the operator to adjust the bottom of the dress in any way or to prepare it for the cutting operation, regardless of the type of dress material, or the size, shape and number of folds in the dress.

Another object is to make the operation of the machine completely automatic upon simply pressing a foot pedal and to eliminate all necessity for the operator to bend over to operate the machine.

A further object is to provide a quick and simple means for interchanging various sizes of dress forms on the machine, so that it may be conveniently used where a wide range of dress sizes are handled.

An additional object is to provide a marking device of this character which enables marking of the dress at any desired distance above the cut, and thereby assists in making an accurate hem.

Referring to the drawings,

Fig. 1 is a vertical section of the complete invention.

Fig. 2 is a horizontal section taken on line 2—2, Fig. 1, but showing the form removed and the form holding means in an unlocked position.

Fig. 3 is a horizontal section taken on the correspondingly numbered line in Fig. 1.

Fig. 4 is an enlarged vertical section of the cutting assembly shown at the left in Fig. 1.

Fig. 5 is a fragmentary horizontal section, on an enlarged scale, taken on line 5—5 in Fig. 1.

Fig. 6 is a fragmentary vertical section, on an enlarged scale, taken on line 6—6, Fig. 1.

In Fig. 1 a hollow central column 16 is fitted to a base 15 forming the main frame of the machine. A tube 90 is fastened within the column 16 and a hollow plug 121 is fastened within the lower end of this tube. A rod 86 is threaded at its lower end, and passes through the plug 121 and above the plug 121, a nut 89 is placed on this rod and below this plug is placed the assembly of a washer 84, a spring 83, between the plug 121 and washer 84 and a nut 85 on this rod below the washer 84. The nut 85 is for the purpose of adjusting the downward pressure of the spring 83 exerted on the rod 86. A foot lever 9 having a pedal is pivoted on the base by a pin 41. The upper end of the tube 90 has a bevel 901 which is in contact with the bevel 921 of a wedge 92, which is fastened to the upper end of the rod 86. A tube 91, which supports a dress form 101, is slidably fitted over the tube 90 and the wedge 92. Normally this wedge is pulled down against the beveled surface 901 of the tube 90 by the spring 83, and exerts a side pressure of the tube 90 and wedge 92 against the inside of the tube 91. This pressure holds the tube 91 and the attached dress form 101 at a fixed height. When the pedal of the foot lever 9 is depressed, the rod 86 is lifted, compressing the spring 83 and raising the wedge 92. The tube 91 is then released and the dress form 101 can be raised or lowered to any desired height. Releasing the foot operated lever 9 causes the wedge 92 to hold the dress form at this height due to the clamping action of the tube 90 and wedge 92 against the tube 91. On the tube 91 is a collar 103 having a knob 102, which collar can be fastened to this tube at any desired position, and when the dress form 101 is lowered until the collar 103 rests upon the upper end of the frame column 16, the height of the dress form 101 is definitely established. Thus, the graduated marks indicated at 126 upon the tube 91 can be used in connection with the collar 103 to indicate the length to which the dress 115 will be cut by the shearing edges 62 and 68 of a cutter mechanism which will be later described.

On the underside or base of the dress form 101 is mounted a large washer or attaching plate 99 to the lower side of which is fastened a shoulder ring 98. This ring is rotatably mounted on the upper side of the plate 97, which is attached to tube 91, this tube being provided axially with an upwardly projecting centering stem or knob 100. On the circumferential part of the plate 97 are pivoted four slotted latches or cams 96. These are turned by four pins or studs 95 on a plate 94 rotatably mounted on the tube 91, these pins engaging with slots 951 in the outer ends of the latches 96. When the plate 94 is rotated on the tube 91 in a direction to move the inner ends of latches or cams 96 away from the axis of the knob 100, these latches 96 assume the position shown

in Fig. 2, in which their inner ends clear the path of the ring 98 and permit the latter to be placed on the plate 97. As shown in Fig. 1, the latches 96 are spaced a short distance above the plate 97. If the latches are now rotated by turning the ring 94 to the left from the position shown in Fig. 1, the inner ends of the latches will overlap the edge of the ring 98, and lock the same in place on the plate 97. By fitting the ring 98 loosely between the plate 97 and latches 96' the dress form can be rotated conveniently by the operator.

Thus, a series of dress forms of various sizes, each equipped with a ring 98, can be quickly attached to or detached from the supporting plate 97 by manipulating the shifting plate 94. To control the motion of this shifting plate, a stationary plate 93 is fastened to the upper part of the tube 91, beneath the plate 94 and the latter is provided with a stop pin or stud 125 which extends into a wide notch or slot 124 formed in the edge of plate 93. The motion of plate 94 is therefore limited by the stud 125 striking either of the sides of the slot 124. A compression spring 122 is placed between the studs 121 and 123 which are mounted, respectively, on the plates 94 and 93. By these means a tension is maintained between the studs 121 and 123 which urges them away from one another and causes the spring 122 to be alternately compressed and expanded as the stud 125 moves from one side of the dead center to the other relative to stud 123. This assures that when the plate 94 is operated, the latches 96 will remain in a completely closed or a completely open position.

A drum-shaped casting 69 is fastened to the central column 16 and a shearing ring or annular cutter 68 is clamped between the top of this drum and a retaining or clamping ring 70 by means of screws 701. When the dress form 101 is adjusted to the proper height by setting the collar 103 as described, the dress 115 is placed on the form and allowed to hang over the edge of the shearing ring 68. An upwardly tapering conical guard 67 is attached to the clamping ring 70, which engages the inner side of the folds of the dress and causes them to fall clear of the top of the clamping ring 70.

Directly beneath the drum 69 a freely rotating turret or supporting gear wheel 17 is mounted upon the column 16 and held in position thereon by collars 21 and 25 secured to the column. Two spaced horizontal guide bars or arms 31 and 32 are mounted in guides 77 and 78 on the rear wheel 17 so as to slide radially thereon, as shown in Fig. 3. Normally these arms and the associated cutting assembly mounted at their outer ends are urged outwardly or to the left in the drawings, by the springs 72 and 73 shown with their center sections broken out in Fig. 3. These springs are attached at one end to a spacer bar 79, fastened to the rear ends of the bars 31 and 32 and at their other ends they are attached to a bar 74, which is rigidly attached to the gear 17 by extension bars 75 and 76 and a bracket 761. Mounted on the hub 24 of the gear 17 are two pulleys 19 and 20, see Fig. 6, each of which has a separate length of cable 22 and 23 looped around it. The upper ends of these cables are clamped to an equalizer bar 29, attached to a bolt 30. The latter is attached to the underside of a plate 47, Fig. 4, forming part of the cutter assembly. Any inward pull on the equalizer bar 29 will slide the horizontal bars 31 and 32 inwardly stretching the springs 72 and 73. The lower ends of cables or flexible lines 22 and 23 are

clamped to diametrically opposite points of upper and lower rings 26, 28 forming parts of a yoke or swivel head which slides vertically on the column 16. The upper and lower rings 26 and 28 are fastened together and a middle ring 27 is recessed into the lower ring and free to rotate between the upper and lower rings. To the upper ring 26 are attached two upright rods or studs 87 and 88 which extend through holes in the gear 17 and compel the rings 26 and 28 to rotate with this gear. Two studs 10 and 11 are attached at their upper ends to the middle ring 27, and extend through holes in a guide collar 45 secured to the column 16, thereby preventing the ring 27 from rotation. The studs 10 and 11 are fastened at their lower ends to a guide plate 14, which surrounds the column 16. Near their lower ends the studs 10, 11 are pivotally secured to the two sections of a foot lever 117 by the studs 12 and 13. The foot lever 117 is pivoted at its rear end to the upper ends of the members of a link 116 which is in turn pivoted at its lower end to the base 15. A downward motion of the foot lever 117 is transmitted to the yoke or swivel and to the cables 22 and 23, which pull the horizontal arm or bar assembly against the pull exerted by springs 72 and 73. Upon releasing the lever 117 the horizontal arm or bar assembly is drawn outwardly by these springs, and the lever 117 is lifted.

Part of the cutting mechanism includes the rotary blade or shearing disc 62 which cooperates with the horizontal shearing ring 68 and moves bodily around the garment support in the manner of a planet and is mounted on the outer ends of the horizontal bars or arms 31 and 32. The cutter shaft 50 which carries the cutter disc 62 rotates in bearings 471, 481, formed on the plate 47 and an upper plate 48 connected with this lower plate by upright posts or spacers 51, 52, 53, as shown in Figs. 1, 3 and 4. The lower plate 47 is attached to the bars or arms 31 and 32. Below the shearing disc 62 the cutter shaft 50 is provided with a sprocket wheel 133 and between the lower and upper plates 47, 48 of the supporting carriage this shaft is provided with a friction drive wheel or pinion 46. As the cutting mechanism moves inwardly by action of the foot lever 117, the friction wheel 46 engages with a rubber tire 71 on the rim 711 forming the base of the drum 69. At the same time the shearing disc 62 is moved inwardly just below the edge of the shearing ring 68. Further motion of the foot lever 117 lifts the disc 62, which is normally held downward by the spring 49 interposed between the upper carriage plate 48 and the friction driving wheel 46 and causes the shearing disc 62 to engage with the shearing ring 68. This is accomplished by the mechanism attached to the equalizer bar 29 which is constructed as follows:

At its center the equalizer bar 29 is provided with a bolt 30, which is pivoted on a lug 40. The latter is attached to the elbow lever 35 which is pivoted on a pin 36, supported by the studs 128 and 129, which are fastened to the lower side of plate 47. Below the lower arm of the lever 35 is arranged a leaf 131, which is normally pressed against the lever 35 by a compression spring 132 interposed between the upper side of the lower arm of this lever and the upper end of a bolt 37 which has its lower end connected with this plate. When an inward pull is exerted on the equalizer bar 29, the leaf 131 exerts an upward pressure on the square bushing 34 which rests on this leaf and engages with a slot 231 at the end of the

lower arm of the lever 35. The bushing 34 acts as a thrust bearing to transmit the upward force to the combination collar and stud 39, which is adjustably mounted on the cutter shaft 50 by providing the upper end of the stud 39 with a screw thread which engages with a threaded opening in the lower end of the cutter shaft and thereby enables the effective length of this shaft to be increased or decreased. After adjustment the stud is held in place against rotation on the cutter shaft 50 by means of the lock nut 38. The stop plate 33 mounted on the underside of the carriage plate 47 is adapted to be engaged by the lower arm of the lever 35 and thereby limit the downward motion of lever 35.

During the initial part of the downward movement of the foot lever to move the cutter carriage inwardly together with the horizontal bars or arms 31, 32 and the cutting assembly, the pull upon the equalizer bar 29 and the upward force upon the bushing 34 is insufficient to compress either of the springs 132 or 49. But when the friction wheel 46 comes in contact with the rubber tire 71, the inward sliding motion of the horizontal arms 31 and 32 is arrested and during the continued downward movement of the foot lever 117 a sufficient force is exerted by the elbow lever 35 and the leaf 131 to lift the shaft 50 and the disc 62 to overcome the spring pressure exerted by 49. The cutter disc 62 is then engaged with the cutter ring 68. Additional motion of the foot lever 117 and the elbow lever 35 will then cause the latter to separate from leaf 131 and compress the spring 132, as shown in Fig. 4.

The springs 72, 73, 132 and 49 are so selected and adjusted that a steadily increasing force applied to the equalizer bar 29 will first stretch the weakest springs 72 and 73. Then when this motion is arrested by the friction wheel 46 striking the rubber tire 71, the spring 49, being the next stronger, will be compressed to allow lifting of the shearing disc 62. Finally when the shearing disc 62 strikes the shearing ring 68, the strongest spring 132 is compressed to maintain a steady and uniform pressure between the shearing edges of the disc 62 and ring 68 regardless of wear of the edges or inaccuracies in alignment of these members or parts associated therewith.

Simultaneously with the compression of the spring 132, the bolt 118 adjustably mounted on the foot lever 117 strikes the push button switch 44 and the lever 119, which holds the bolt 118 on the foot lever 117, is pressed against the latter by a spring 120. This spring allows additional motion of the foot lever 117 after the switch 44 has been closed. The operation of the switch 44 starts the motor 80, which drives the gear 17 by means of the pinion 82. The latter is not directly connected to the motor shaft, but is driven through a friction clutch 81, which is adjusted to slip if the mechanism jams and the torque delivered by the motor exceeds a safe value.

The motor 80 is supported on the main frame of the machine by the bracket 43, which is in turn fastened to the column 16 by the U-bolt 42 and the collar 45.

The rotation of gear 17 by the motor 80 causes the cutting assembly to swing around the dress. The friction wheel 46, being in contact with the tire 71, is rotated on its axis and drives the shearing disc 62, while the assembly as a whole is moving around the drum 69. Since the lower

edge of the drum 69 is of larger diameter than the shearing ring 68, and since the shearing disc 62 is of larger diameter than the friction wheel 46, the shearing disc 62 is rotated at a relatively higher peripheral speed. Thus, it effects a wiping cutting action in addition to the shearing action it would have if it merely rolled around the shearing ring 68.

To assist in starting the shearing action, the shearing edges of 62 and 68 are slightly inclined to each other. As shown in Fig. 6, the upper and lower faces of the gear 17 are not strictly parallel, the upper face being slanted slightly so that the gear as seen is thinner at the right edge of Fig. 6. Thus, the cutting assembly mounted on the bars 31 and 32 is slightly tilted, and the disc 62 is not strictly parallel with the shearing ring 68, thereby causing the operative cutting edge portion of the shearing disc 62 to be tipped upwardly as it approaches the operative cutting edge portion of the shearing ring 68, whereby the operative parts of these shearing members are held in their most effective relation and a clean cut of the dress is produced for trimming or sloping the same.

The foot lever 117 is held down while the shearing disc 62 is traveling around the ring 68. When the dress trimming operation is complete, the lever 117 is released, causing the motor to stop and the cutting assembly to move away from the shearing ring 68.

Smoothing means are provided for use in connection with the cutting assembly to assure that the pleats and folds in the dress are brought to the shearing members in their natural positions, undisturbed by the motion of the shearing disc 62. Any disarranging of the natural positions of the pleats and folds, except a radial compression of the folds towards the shearing ring 68, will cause a scalloped or uneven cut. The smoothing mechanism to produce this effect is mounted on the plates 48, 59 of the cutter carriage and constructed as follows:

A driving sprocket wheel 133 on the shaft 50 rotates a driven sprocket wheel 106 and a rear retaining pulley 105 connected therewith by means of a chain belt 104 passing around these sprocket wheels, said driven sprocket 106 and pulley being mounted on a shaft 206 which is journaled on the plates 48, 59 of the cutter carriage. Two belts 57 and 58 pass around the pulley 105 and an intermediate retaining pulley 110 and, respectively, the idler pulleys 55 and 56. The rear and front retaining pulleys 105, 110 are arranged in front and in rear of a line extending from the axis of the drum 69 to the axis of the cutter shaft 50 and adjacent to the periphery of this drum. The idler pulleys 55, 56 are arranged below and above the outer part of the cutter disc and these idler pulleys are mounted, respectively, on tightening levers 108 which are pivoted on a post 107 of the cutter carriage and each is pulled outwardly for keeping the respective belt taut by means of a spring 109 connecting the respective tightening lever with the adjacent part of the cutter carriage, as shown in Fig. 2. The belt 57 is below the shearing disc 62 while the belt 58 is arranged above it.

A second intermediate pulley 112 is journaled on the plate 48 of the cutter carriage in front of the pulley 110 and is driven from the latter by the group of three intermediate retaining belts 111 passing around the pulleys 110, 112 above the plane of the cutter members 62, 68. This pulley 112 in turn drives a front pulley 114

by means of a group of three front retaining belts 113 arranged above the plane of the cutting line, this front pulley being journaled on the foremost part of the plate 48 of the cutter carriage. By this means a system of retaining belts is provided which extends along the periphery of the drum from a point in rear of the cutting station to a point considerably in front of this station and which belts cooperate with the adjacent surface of the drum for holding the dress above the cutting line so that the same is not displaced during the operation of trimming the same by the cutters 62, 68.

As the cutting assembly is moved inwardly prior to beginning the cutting operation, the belts 57 and 58 hold the dress firmly against the drum above and below the shearing ring 68 for a considerable distance around the circumference of the dress and the drum, but the belts 111 and 113 do not press throughout their length against the drum but operate mainly to gather the garment inasmuch as they form, with the adjacent part of the drum, a rearwardly converging passage or throat whereby the body of the garment and any pleats therein are held in place and directed to the cutting station in a proper non-misplaced condition. This is of considerable help in starting the cut and in securing a positive cutting action of the cutters on the dress. As the cutting members begin to rotate, the belts 57, 58, 111 and 113 are driven in the direction of the arrows associated with the same in Fig. 2. The speeds of the belts are so determined that there is little or no relative motion between these belts and the dress. Although the cutting assembly is rotating clockwise around the dress, that side of the belt system opposite to the dress is moving in the opposite direction so that the resultant motion with respect to the dress is zero. As a result the belt retaining system produces a substantially radial compression of the folds of the dress, regardless of their shape or size.

The relative dimensions of the stepped pulleys 110 and 112 are such that successive belt groups are driven at a slightly higher speed than the preceding ones. The intermediate belt group 111 travels slightly faster than the rear belt group 57 and 58, and front belt group 113 travels slightly faster than belt group 111. It will thus be noted that the belt groups farthest away from the center or cutting station of the dress run at slightly higher speeds. By a proper selection of the speeds and positions of these retaining belts, very satisfactory results can be secured under all operating conditions. The belt groups 111 and 113 are preferably elastic to simplify the problem of keeping them tight.

For the purpose of marking the dress to indicate where the same should be folded while hemming the same, means are provided for effecting such marking at the same time the dress is being trimmed, these means being preferably constructed as follows:

The numeral 65 represents a cup or receptacle adapted to contain a light powder 233 and arranged above the upper plate 59 of the cutter carriage and provided in the lower part of its side wall facing the drum 67 with an outlet 651 through which the powder is discharged. The bottom 652 of this container slopes toward the outlet thereof so as to direct the powder to said outlet. This container is supported on the plate 59 by a post 66 rising from said plate and passing through a lug 230 on the outer side of the container on which the latter may be adjusted ver-

tically and held in place by a set screw 130. The powder is withdrawn from the container by a marking wheel 64 which with one part of its periphery enters the outlet 65 to withdraw the powder 5 while the diametrically opposite part thereof is adapted to engage the outer side of the dress on the guard 67 above the trimming line. This marking wheel is held against vertical movement between upper and lower brackets 641, 642 10 arranged on the adjacent part of the powder container 65. Rotation of this marking wheel is affected by an upright shaft 63 journaled in a bearing on the plate 59 provided at its lower end with a gear wheel 60 which meshes with a gear wheel 61 secured to the upper end of the cutter shaft 50. The upper part 631 of the marker shaft is square or of other non-circular form and passes through a correspondingly shaped hole in the center of the marking wheel and 15 through the adjacent parts of the brackets 641, 642, as shown in Figs. 1 and 4. As the container and marking wheel are shifted vertically a driving connection is maintained between this wheel and shaft. The post 66 may be provided 20 with graduations, as shown, to facilitate adjustment of the marking apparatus for varying the position of the mark relative to the lower edge of the dress for producing a hem of any desired width.

30 I claim as my invention:

1. In combination with a garment supporting stanchion having a base, a tubular column fixed to said base, a vertically adjustable tubular member having the lower end thereof telescoping into said tubular column, and a garment form secured to the upper end of said tubular member, of a fixed tubular member secured within said tubular column and having the upper portion thereof extending into said vertically adjustable tubular member, a cylindrical wedge member having a mitered lower end fitting over the correspondingly mitered upper end of said fixed tubular member, an operating rod secured to said wedge member, a resilient member associated with said rod for urging said wedge member into frictional locking engagement with said vertically adjustable tubular member, and manually operated means for manipulating said rod to release said wedge member from locking engagement with said vertically adjustable tubular member.

2. A garment supporting stanchion including, a base, a tubular column fixed to said base, a vertically adjustable tubular member having the lower end thereof telescoping into said tubular column, a garment form secured to the upper end of said tubular member, a fixed tubular member secured within said tubular column and having the upper portion thereof extending into said vertically adjustable tubular member, a cylindrical wedge member having a mitered lower end fitting over the correspondingly mitered upper end of said fixed tubular member, and means for manipulating said wedge member into and out of frictional locking engagement with said vertically adjustable tubular member.

3. In a garment trimming machine, a base, a tubular column fixed to said base, a vertically adjustable tubular member having the lower end thereof telescoping into said tubular column, a garment form, means for securing said garment form to the upper end of said tubular member, a member having a tubular wall supported on said column around which the lower portion of the garment may drape, a cutting disc adjacent

said tubular wall, markings on said tubular member indicating the length of the garment supported on said form relative to the position of said cutting disc, and means for releasably securing said tubular member in predetermined vertically adjusted position.

4. A garment supporting stanchion adapted for association with a garment trimming machine including, a base, a tubular column fixed to said base, a vertically adjustable tubular member having the lower end thereof telescoping into said tubular column, a garment form secured to the upper end of said tubular member, a fixed tubular member secured within said tubular column and having the upper portion thereof extending into said vertically adjustable tubular member, a cylindrical wedge member having a mitered lower end fitting over the correspondingly mitered upper end of said fixed tubular member, an operating rod secured to said wedge member, a collar secured within the lower end of said fixed tubular member through which the end of said rod extends, a collar secured to the end of said rod, a coil spring seated between said collars operative to exert a downward pull on said rod and urge said wedge member into frictional locking engagement with said vertically adjustable tubular member, and a manually operated foot lever for lifting said rod to release said wedge member from locking engagement with said vertically adjustable tubular member.

5. In combination with a garment trimming machine having a base, a tubular column fixed to said base, a vertically adjustable tubular member having the lower end thereof telescoping into said tubular column, and a garment form supported on said tubular member, of means for detachably securing said garment form to the upper end of said tubular member, said means including a supporting plate secured to the upper end of said tubular member, a conical knob portion projecting upwardly from said plate, a plate secured to the lower end of said garment form adapted to rest on said supporting plate and hav-

ing a centering aperture through which said conical knob portion extends, and cooperating interlocking means associated with said plates effective to lock and unlock said plates together upon relative rotation thereof.

6. In a garment supporting stanchion having a base, a supporting post supported by said base, a garment form supported on said post, and means for detachably securing said garment form to said post, said means including a supporting plate secured to the upper end of said post, a knob formation projecting upwardly from said plate, a plate secured to the lower end of said garment form adapted to rest on said supporting plate and having a centering aperture through which said knob formation extends, and cooperating locking means associated with said plates effective to lock together and unlock said plates upon relative rotation thereof.

7. In combination with a garment trimming machine having a base, a tubular column fixed to said base, garment cutting mechanism supported by said column, a vertically adjustable tubular member having the lower end thereof telescoping into said tubular column, and a garment form secured to the upper end of said tubular member, of a fixed tubular member secured within said tubular column and having the upper portion thereof extending into said vertically adjustable tubular member, a wedge member having a mitered surface fitting over a correspondingly mitered surface at the upper end of said fixed tubular member, an operating rod having the upper end thereof secured to said wedge member, a resilient member supported by said rod and engaging a fixed abutment, said resilient member being operative to urge said wedge member into frictional locking engagement with said vertically adjustable member, and a foot pedal for manipulating said rod to release said wedge member from locking engagement with said vertically adjustable member.

HENRY LEHDE.
